UNITED STATES PATENT OFFICE.

JOHN C. DETTRA, OF OAKS, PENNSYLVANIA, ASSIGNOR TO JOHN C. DETTRA & COMPANY, INC., OF OAKS, PENNSYLVANIA, A CORPORATION OF PENNSYLVANIA.

TOY.

1,235,771.

Specification of Letters Patent.

Patented Aug. 7, 1917.

Application filed December 21, 1916. Serial No. 138,185.

To all whom it may concern:

Be it known that I, JOHN C. DETTRA, a citizen of the United States, and a resident of Oaks, county of Montgomery, and State 5 of Pennsylvania, have invented a certain new and useful Toy, of which the following is a specification, reference being had to the accompanying drawings.

A principal object of my invention is to 10 provide an entertaining and amusing toy which can be safely operated by children and which shall be simple in construction and not liable to get out of order even though subjected to relatively hard usage. 15 My invention further comprises all of the various other objects and novel features of construction and arrangement hereinafter more definitely specified and described.

In the accompanying drawing, Figure 1 20 is a perspective view illustrating the operation of the invention; Fig. 2, a horizontal section partially broken away through one of the parts of the invention and Fig. 3 a vertical section taken on line 3—3 in Fig. 2.

25 The form of the invention illustrated in the drawings comprises a pair of members A and B which may preferably be constructed to resemble naval vessels and will hereinafter for convenience be respectively referred to as the "battleship" and the "cruiser". The former, which may preferably be constructed of wood or other suitable material, may comprise a bottom 1, sides 2—2 and a deck 3 secured together and 35 forming the hull which is provided with a central cavity 5. For convenience of construction a pair of solid end blocks 6—6 may be secured to the bottom to support the deck 3, and the sides 2—2 fastened to the end blocks and to the bottom and deck, or the sides and ends may be made from one piece of material, or, if desired, the hull may be constructed in any other convenient manner.

To more nearly complete the resemblance of 45 the battleship to a naval vessel a superstructure 7 may be secured to the deck and arranged to support turrets 8, masts 9 and funnels 10 which may be provided with studs 12 arranged to engage in sockets in 50 the superstructure, as best shown in Fig. 3, so that these parts may be removed when desired to facilitate packing and transportation.

The battleship may be provided with a 55 laterally projecting preferably spring actu-

ated cannon or gun 15 stationarily supported with respect to the hull and adapted to discharge a cylindrical projectile 16, and while the gun may be of any suitable or preferred construction, that shown in the drawings comprises a chamber 17 in which is positioned a coil spring 18 carrying a head 19, the bore of the chamber being greater than that of the barrel of the gun so that a shoulder 20 is formed at the forward end of the chamber against which the head 19 is adapted to strike when the gun is discharged. Forward of the chamber the gun is provided with a transverse slot 22 in which a spring 25 is adapted to normally engage, one end of the spring being secured to a suitable portion of the hull, as, for example, one of the blocks 6 in such manner that the spring, adjacent its other end, will freely enter the slot and normally rest 75 on the bottom thereof, as best shown in Fig. 3. The projectile 16 is preferably cylindrical in form and provided adjacent its rear end with a peripheral groove 27 so positioned that when the projectile is inserted 80 in the gun and pushed home therein to compress spring 18 as shown in Fig. 3, spring 25 will ride up on the projectile, which may preferably be tapered toward its rear extremity to facilitate this action, and engage 85 in groove 27 when the projectile has been inserted sufficiently far to bring the groove into registry with the slot, thus retaining the projectile in the gun against the compression of spring 18.

90 For the purpose of raising spring 25 out of groove 27 at the proper time, as herein-after described, and thereby releasing the projectile, a suitable trigger 30 is provided and pivoted, preferably substantially beneath the gun, to the bottom 1 of the hull by a pivot pin 31 to permit of its rotation in a horizontal plane about the pivot, the ends of the trigger being arranged to project beyond the sides of the hull through a 95 pair of oppositely disposed slots 34 therein. The free end of spring 25 which projects beyond the gun is turned downwardly and then horizontally to form a foot 35, and the edge of the trigger adjacent the spring is 100 suitably beveled, as at 36, so that as the trigger is moved about its pivot it may be caused to lift spring 25 by engagement of the beveled portion of the trigger therewith for a sufficient distance to lift the 110

spring from groove 27 and thus release the projectile to be forcibly discharged from the gun under the action of spring 18.

The cruiser B may preferably be composed of a number of separate pieces or blocks assembled on a base or bottom 40 in such manner as to resemble a naval vessel, as best indicated fragmentarily in dotted lines in Fig. 1, and may comprise end 10 pieces 41, center pieces 42 from which a considerable portion of the hull and superstructure is composed, masts 43 and funnels 44, although of course the form and arrangement of the blocks may be varied as 15 desired, the object being to provide a number of separate units which may be assembled on the base so as to resemble a vessel or the like. To facilitate the operation of the invention, it is preferable to make the 20 blocks as light as possible, for example by forming them of channel section as shown instead of solid. One end of base 40 is provided with a screw-eye 45 or the like for the convenient attachment of a relatively stiff 25 wire or rod 46 having a hook 47 at one end adapted to engage the screw-eye, the other end of the wire being arranged for insertion in a hole 48 in that end of the trigger 30 adjacent the muzzle of gun 15.

30 The parts having been constructed preferably substantially as described and shown, the operation of the invention may be briefly indicated as follows: The separate blocks are first arranged upon base 40 to form the 35 cruiser as fragmentarily shown in dotted lines in Fig. 1, the wire inserted in the trigger and hook 47 engaged in screw-eye 45, the trigger being positioned substantially as shown in dotted lines in Fig. 1, which will 40 bring the cruiser into a position considerably astern of the battleship. The projectile is next inserted in the gun until spring 25 engages in groove 27, and the trigger then rotated about its pivot by grasping the end 45 of the trigger opposite to that in which the wire is inserted thereby causing the cruiser to move relatively to the battleship until it is substantially abreast thereof when the trigger will have been rotated sufficiently 50 far to lift spring 25 and release projectile 16 which strikes the built up portion of the cruiser with sufficient force to scatter the blocks from which it is constructed in numerous directions, thus giving an appearance 55 substantially similar to that which might occur upon the blowing up of a vessel. Of course it will be understood that the blocks from which the cruiser is constructed are not materially injured by the impact of 60 the projectile and hence the cruiser may be reconstructed and the toy operated as often as desired without material wear upon, or injury to, the various parts.

While I have herein illustrated and 65 scribed one embodiment of my invention

with considerable particularity I do not thereby desire or intend to limit myself solely thereto, as suitable changes and modifications may be made in the form and arrangement of the various parts, and the 70 external appearance of those elements of the invention which I have, for convenience, herein designated as the "battleship" and the "cruiser" may be varied as desired from that shown in the drawings, without departing from the spirit and scope of my invention as defined in the appended claims. 75

Having thus described my invention I claim and desire to protect by Letters Patent of the United States:—

1. A toy comprising relatively movable members, one of said members having means operative to discharge a projectile, means operative to move the other of said members with respect to said first-mentioned member 85 and means operative to discharge a projectile when said relatively moving member has reached a predetermined position with respect to said relatively stationary member.

2. A toy comprising relatively movable 90 members, one of said members being composed of a plurality of separate pieces, means upon the other of said members operative to discharge a projectile, means connecting said members, means operative to move said 95 first-mentioned member with respect to said last-mentioned member, and means operative to actuate said projectile discharging means when said first-mentioned member has reached a predetermined position with respect to said last-mentioned member.

3. A toy comprising a pair of relatively 100 movable members, means on one of said members operative to discharge a projectile in a predetermined direction with respect to 105 said member, means connecting said members and operative to cause the movement of the other of said members with respect to said first-mentioned member to bring said member into the line of flight of the projectile, and means operative to cause the discharge of a projectile when said member is 110 in said line of flight.

4. A toy comprising a pair of independently movable members, means connecting 115 said members, means upon one of said members operative to discharge a projectile, a projectile, means operative to move said connecting means to cause relative movement between said members and means operative 120 to discharge said projectile when said members have been moved to assume a predetermined position.

5. A toy comprising a member formed to 125 resemble a vessel and having means operative to discharge a projectile, a second member composed of a plurality of separate blocks assembled to form the member, means operative to connect said members, means co-operative with said connecting means to 130

- cause relative movement of said members, and means operative to cause the discharge of a projectile from said projectile discharging means when said members are moved 5 into a predetermined relative position.
6. A toy comprising a pair of members each constructed to resemble a vessel, one of said members being formed from a plurality of separate units, means upon the other of 10 said members operative to discharge a projectile in a predetermined path with respect to said member, means connecting said members, means operative to cause the movement of said connecting means and said first- 15 mentioned member to bring said member into the path of said projectile and means operative to cause the discharge of the projectile after said member has moved into the path thereof.
20. 7. A toy comprising a member having a spring operated gun adapted to discharge a projectile, a second member comprising a plurality of independent units, means operative to connect said members, means operative to cause the relative movement of said 25 members through said connecting means and

means to cause the discharge of a projectile from said gun when said second member is moved into a predetermined position with respect to said first-mentioned member. 30

8. A toy comprising a member formed to resemble a vessel and having a laterally projecting spring operated gun adapted to discharge a projectile, a second member comprising a plurality of independent pieces assembled to form the completed member, means connecting said members, means comprising a trigger pivoted to said first-mentioned member and operative to cause the movement of said connecting means to draw 35 said second member into a predetermined position with respect to said first-mentioned member, and means operative to cause the discharge of a projectile from said gun against said second member when said 40 member has been brought into a predetermined position with respect to said first member. 45

In witness whereof, I have hereunto set my hand this 14th day of December, A. D. 50 1916.

JOHN C. DETTRA.
